CONTAINER COVER

Elmer H. Wilkinson, New York, N. Y., assignor to
Tri State Cap & Cap Machinery Co., Inc., New-
ark, N. J., a corporation of New Jersey

Application September 23, 1935; Serial No. 41,704

3 Claims. (Cl. 215—38)

This invention relates to container covers and particularly to container covers of paper commonly termed hood container covers. The invention relates especially to such container covers

5 which do not contain metallic fastening means.

The principal object of the invention is to provide a hood container cover for bottles and other containers, of improved construction and mode of applying it to the same. The said container 10 cover comprises a central or container mouth covering portion and a skirt portion depending therefrom embodying a plurality of sections of substantially equal height but of different widths and ending in tabs ordinarily separated by slots. 15 Certain of said tabs are preferably pre-cemented or coated with adhesive on one side. When the container cover is in final position on the container, certain of the tabs are folded inwardly and upwardly and pressed into contact with the adjacent parts of the skirt portion and tend to prevent unfolding of the same.

Another object is to form certain of the sections so that interlapping of inwardly folded tabs is attained and final cementing or securing of the 20 interlapping tabs is effected. A further object is to effect the foregoing results with the use of a cement or adhesive which is preferably waterproof and which softens by the heating of the pre-cemented parts, and also to provide a method 25 of applying the container covers in which final securing of the tabs is effected by applying heat and pressure around the neck of the container, and on removing the pressure the sections will remain in place by reason of the inward and upward folding of the tabs and until the cement or adhesive becomes sufficiently set to secure a more permanent union of the parts.

Certain container covers have been proposed 30 having blanks of circular form with an unbroken outer edge. These when placed on container necks are formed into a series of sections separated by plaiting all extending in one direction and the lower part of the blank is folded inwardly and upwardly to retain the cover in place on the container neck. This construction involves an operation of folding which is very difficult and expensive to effect satisfactorily on any practical capping machine. Furthermore this form of cover is difficult to remove from the container top 35 when it is desired to use the contents of the container. My improved container cover avoids the foregoing difficulties and is readily applied by machine and has improved means for removing it from the container.

55 Embodiment of the means I prefer to employ

for effecting the above objects, together with other advantageous features, are illustrated in the drawings accompanying and forming part of this specification, and in which—

Figure 1 is a plan of one form of blank for my 5 improved container cover.

Fig. 2 is a front elevation partly in vertical section on the line 2—2 of Fig. 3, of this form of the invention as applied to the upper part of a container.

Fig. 3 is a top plan of the same.

Fig. 4 is a side elevation of part of the container top and with the cover in section on the line 4—4 of Fig. 2.

Fig. 5 is a similar view with the cover in section 15 on the line 5—5 of Fig. 2.

Fig. 6 is a plan of a blank for another form of the invention.

Fig. 7 is a front elevation partly in vertical section of this form of the invention.

Fig. 8 is a plan of a blank for a third form of the invention.

Fig. 9 is a front elevation of the same with the cover partly in vertical section.

Fig. 10 is a plan of a blank for another form of 25 the invention.

Fig. 11 is a front elevation of the same as applied to a container and with the cover partly in vertical section.

Fig. 12 is a plan of another form of blank.

Fig. 13 is a front elevation of this form as applied to a container and with the cover partly in vertical section, and

Fig. 14 is a plan of another form of the invention.

Referring to Figs. 1 to 5 inclusive of the drawings, the numeral 2 indicates one form of blank for my improved container cover and it is composed of a central or container mouth covering portion 3 formed by scored or creased lines 4 and preferably of polygonal form, said portion being folded down along said lines when applied to a container mouth. Joined to the edges 4 of the container mouth covering portion are the flaps or sections 5 which are all substantially of equal height. As shown in Fig. 1 the sections 5 are of different sorts alternating with one another and separated by triangular portions 6, which when the cover is on the container are developed into folds such as 7 and 8.

50 Preferably the sections 5 all end in tabs but the latter may be of different shapes. They are all substantially of the same height as indicated in Fig. 2. In the form of blank shown in Fig. 1 the numbers 10 and 11 refer to the two different sorts

of sections shown in this form, and said sections respectively end in the tabs 12 and 13. The tabs 12 are pre-cemented or coated with cement or adhesive 14 and the tabs 13 are also pre-coated 5 with the same.

In applying a cover to a container, a blank 2 is placed on the container mouth *m* of the container C and the sections 5 are pushed down around the container neck, the wider sections 10 being pushed down first. The tabs 12 are next pushed into place and may be pre-folded along 15 the scored lines 16, and when this is the case their side parts 17 extend over the line 8a which define one of the folds 8 at its upper part and 20 defines the slot 18 at its lower part.

The tabs 13 are next pushed in behind the other skirt parts as shown in Fig. 2 and pressure is brought to bear all around the container neck *c* and where the cement is adapted to be softened 25 by heat, the same is also applied to the skirt portion, preferably by suitable folder members such as those containing electric heating coils.

It will be noted that the parts 17 of the tabs 12 constitute interlocking pre-coated tabs with 25 the tabs 13 which are positioned behind them. The interlocking tabs on being heated and cooled 30 preferably under pressure, form so firm a union that tampering with the cover is practically impracticable. Furthermore such tampering 35 would render the package unsalable.

The form of the invention shown in Figs. 6 and 7 is similar to the foregoing but differs therefrom partly in having less depth in the slots 18 and also in being of an octagonal form at the 35 central or mouth covering part, so that the various parts assume a somewhat different relation to each other than those in Figs. 1 to 5 inclusive.

The form shown in Figs. 8 and 9 differs from the foregoing forms by the elimination of the 40 slots 18 and in extension of the triangular parts 6, and differs from the form in Figs. 6 and 7 by having the central portion hexagonal.

In the form of the device shown in Fig. 10, the blank 20 is of a circular form and has a scored 45 polygonal central portion 22 surrounded by the flaps or sections 23 and 24 of substantially equal height scored therein, triangular scored portions 25, and tabs 26 and 27 of substantially equal height but of greatly different widths and 50 separated by the slots 28.

Fig. 11 shows the application of this blank to a container neck and wherein the tabs 27 are first folded between the skirt portion 21 and the container neck, and the tabs 26 are then folded 55 between the skirt portion 21 and the container neck and the extensions 29 of the tabs 27 extend under the flap 23. The folds or plaits 30 point toward each other. Cement 31 is indicated on the tabs 26 and 27 and may be of the variety which softens by heating it or only one set of the tabs may be coated with that variety and the other set may have another sort of cement or adhesive so that it will be more difficult to 60 undue the parts from one another.

Fig. 12 shows a blank 32 in which flaps or 65 sections 33 and 34 surround the central or container mouth covering portion 35 and are separated by triangular portions 36 and slots 37, all

of which parts except the slots are formed by scorings. The naps 33 are provided with tabs 38 and 39, and the flaps 34 have tabs 40 which may sometimes be pre-folded on the lines 41. The tabs 38 are folded behind the flaps 33 and 5 the ends 42 of the tabs 40. The slots 37 extend deeply into the blank for greater facility of the tab folding operations. Fig. 13 illustrates the blank 32 as applied to a container top and in this figure all the tabs except the tabs 39 are 10 folded between the container neck and the adjacent parts of the skirt portion. The tabs 39 lie full length against the container neck and there are scorings 44 or sometimes lines of perforations 44a, so that the strip 45 can be torn 15 out of the flap 33 on pulling the tab 39 upwardly. There being several of tabs 39, a failure of one will not prevent the container from being opened by use of the tearing tab as it is very unlikely that all of them would fail. 20

In the form shown in Fig. 14, 33a and 34a are the flaps or sections, 35a is the container mouth covering portion, 36a are the triangular portions and 37a are the slots separating the sections. 38a and 39a are the tabs on sections 34a, and 25 46 denotes the tabs on sections 33a. 44a indicates the rows of perforations defining the strips 45a. From the drawings it will be clear that this form is similar to that of Fig. 12 except that the tearing tabs 39a are on the wider 30 flaps 34a.

What I claim is:—

1. A container cover comprising a container mouth covering portion, a skirt portion depending therefrom and including a plurality of sections of equal height at their central parts, ending in tabs of equal height, the tabs defined at their sides by slots in the blank and folded inwardly between the container neck and the adjacent skirt parts, the adjacent side portions of the tabs interlapped with each other, and means on the adjacent surfaces of said side portions for holding the tabs in the interlapped position. 35

2. A container cover comprising a container mouth covering portion, a skirt portion depending therefrom and including a plurality of sections of equal height at their central parts, ending in tabs of equal height, the tabs defined at their sides by slots in the blank, alternate tabs being 40 wider than the intermediate tabs, all of the tabs being folded inwardly between the container neck and the adjacent skirt parts, the adjacent side portions of the tabs interlapped with each other, and adhesive means on said side portions for holding the tabs in the interlapped position. 45

3. A container cover comprising a container mouth covering portion, a skirt portion depending therefrom and including a plurality of sections of equal height at the central part, each ending in a tab, said sections separated by depending lapped elements, said tabs folded between the container neck and the adjacent skirt parts secured thereto by non-metallic means, and a downwardly disposed tearing strip in one of said sections free of the folded and lapped parts. 50
